UNITED STATES PATENT OFFICE

CLIFFORD T. SONDELEY, OF NEWBERRY, SOUTH CAROLINA

BEARING GROOVING AND POCKETING MACHINE

Application filed October 4, 1928. Serial No. 310,424.

This invention relates to machines for forming oil grooves and pockets in the bearings at the crank ends of connecting rods and more particularly the connecting rods of 5 internal combustion engines.

An important object of the invention is to produce a device of this character which will be universal in its use and enable the formation in the bearing of any type of oil 10 groove or pocket which may be desired.

A further object of the invention is the provision in a device of this character of an arrangement permitting adjustment of the structure to accommodate bearings of 15 different diameters and different widths and of means for mounting the connecting rods for an operation which means is adjustable so that rods of different sizes may be taken care of.

20 A still further object of the invention is to provide a device of this character which is simple in its construction and arrangement, which will be durable in service and which may be readily and cheaply manufactured.

These and other objects I attain by the construction shown in the accompanying drawings, wherein for the purpose of illustration is shown a preferred embodiment of my invention and wherein:

Figure 1 is a side elevation partially in section of a bearing grooving and pocketing machine constructed in accordance with my invention;

25 Figure 2 is a side elevation of a different type of cutter which may be employed in the machine;

Figure 3 is a section on the line 3-3 of Figure 1;

40 Figure 4 is a detail sectional view through a bearing showing the operation performed by the cutter of Figure 3;

Figure 5 is a bottom plan view of this bearing;

45 Figure 6 is a detail sectional view showing a pocketing operation taken on the line 6-6 of Figure 1;

Figure 7 is a detail sectional view through a bearing showing the operation performed 50 by the cutter of Figure 6;

Figure 8 is a plan view of a grooving cutter;

Figure 9 is a bottom plan view of a bearing showing the groove formed by the cutter of Figure 8 and a further modification of transverse groove which may be produced with the cutter of Figure 3;

Figure 10 is a detail view showing the gauge against which the connecting rod is 55 rested in associating the same with the cutter of Figure 6;

Figure 11 is a sectional view showing the mounting of the pivot for the connecting rod when employed with this cutter.

Referring now more particularly to the drawings, the numeral 10 indicates a suitable base having arising therefrom bearings 11 in which is disposed a cutter shaft 12. This shaft may be rotated in any suitable manner, being at present shown as provided with a 60 pulley 13 for operation by a belt from a suitable source of power. Opposite ends of the shaft are socketed, as at 14 and 15, for the reception of cutter mandrels. In Figure 1, the socket 14 is shown as having disposed 65 therein a mandrel 16 provided with a broad faced cutter 17, the purpose of which will 70 hereinafter appear.

For this mandrel may be substituted a 75 mandrel 18 having a narrow faced cutter 19 for the performance of special work. The socket 15 mounts a mandrel 20 having a narrow faced cutter 21 similar to the cutter 19 and this mandrel may be removed and other 80 mandrels of different sizes substituted, when 85 so desired.

Associated with the mandrel 15 and arising from the base 10 are a pair of brackets 22, each having a horizontal upper end 23 from which arises a pin 24. The pins 24 are diagonally disposed with relation to 90 each other and arranged at opposite sides of the general plane of the cutter, as more clearly shown in Figure 8, and are spaced to extend into the openings 25 in the crank bearing end of a connecting rod 26 as shown in 95 Figure 9.

It will be obvious that these pins will maintain the bearing at an angle with the result that the face thereof, when the bearing is forced downwardly upon the pins, will 100

gage with the cutter 21 and have formed therein a diagonally extending oil groove 27, as more clearly illustrated in Figure 9. It will be obvious that by substituting for the cutter 21 and its mandrel 20 a cutter of the proper size, such grooves may be formed in bearings of any desired diameter.

The mandrel 16 overhangs one end of the base and at this end, as shown in Figure 11 10 the base is provided adjacent its lower end with a pair of vertically extending guides 30 between which is mounted the shank portion 31 of a wrist pin 32. Rotatably mounted between the guides is a threaded stem 33 which is directed through the shank 31, so that by 15 rotation of this stem, the shank may be raised or lowered or completely removed to permit its substitution by a wrist pin of a different size. Above the guides, the end of the base has projecting therefrom a pair of bolts 34, 20 more clearly shown in Figure 10, these bolts mounting at their opposite ends a slide plate 35 adapted to abut the side face of a connecting rod, the head end of which is engaged 25 with the pin 32.

Adjustment to compensate for the width of the connecting rod being acted upon may be had by means of washers 36 or other suitable devices. The pin 32 acts as a pivot for 30 the connecting rod, permitting the same to be oscillated from one side to the other, so that the cutter may act upon opposite faces thereof to form the oil pockets 37, as shown in Figure 7 in the bearing, which do not extend 35 through the side faces of the bearing. By the adjustment at 33, the height of the bearing may be so regulated that this pocket is equally distributed between the two sections in which such bearings are ordinarily formed.

40 In addition to the diagonal type of oil groove, the bearings are provided with transverse grooves, some of which, as illustrated in Figures 4 and 5, as at 38, open through the side faces of the bearings and others of which, 45 as indicated in Figure 9 at 39, terminate short of the edges of the bearings. Each of these grooves is formed by use of the mechanism more particularly illustrated in Figure 3 and shown in partial cross section in Figure 1. 50 This mechanism includes a standard 40 arising from one side of the base and having pivoted to its upper end a table 41. At its free edge, the table has legs 42 which are adjustable as to length and are adapted to engage 55 the upper surface of the base to determine the effective height of the table at the middle thereof. The middle of the table has an opening 43 through which extend the 60 diagonally disposed cutting faces 44 of a compound reamer secured to the shaft 12. To the upper surface of the table is removably secured a transversely extending semi-circular bar 45, which may be removed and replaced 65 with bars of different sizes. This bar at its

middle is notched, as indicated at 46, to accommodate the periphery of the reamer and to expose the cutting faces thereof.

It will be obvious that the vertical height of the table will determine the extent to which the reamer faces are exposed and by placing a proper bar 45 to interiorly fit the bearing section, this bearing section may be slid over the reamer as it is in operation to form the cut or oil groove of Figures 4 and 5. To 70 form an oil groove, such as shown at 39 in Figure 9, the bearing section is simply forced vertically downwardly upon the reamer.

It will be obvious that by use of apparatus of this character, practically any grooving or pocketing operation desired can be performed and the operation will require but a 75 very short time.

Since considerable modification might be resorted to without in any manner departing from the spirit of my invention, I do not limit myself to the specific structure hereinbefore set forth except as hereinafter claimed.

I claim:—

1. In apparatus for forming a diagonal oil groove in bearings which are formed in sections each of which has a pair of apertured ears disposed in a plane at right angles to the bearing for the reception of securing elements holding the sections in assembled relation, said apparatus comprising a shaft, means for rotating the shaft, a cutter carried thereby, and a pair of pins diagonally disposed with reference to each other and to the shaft, said pins being arranged at opposite sides of the shaft and at opposite sides of the cutter adapted to engage in the apertures of the ears and guide the bearing section for engagement with the cutter. 105

2. In apparatus for forming a diagonal oil groove in bearings which are formed in sections each of which has an apertured ear for the reception of securing elements holding the sections in assembled relation, said apparatus comprising a shaft, means for rotating the shaft, a cutter carried thereby, and a pair of pins diagonally disposed with reference to the shaft and each other and arranged at opposite sides of the shaft and at opposite sides of the cutter adapted to engage in the apertures of the ears and guide the bearing section for engagement with the cutter, there being supports for said pins limiting the downward movement of the bearing to thereby regulate 110 the depth of the cut. 115

3. In apparatus for forming oil pockets in the crank shaft bearings of connecting rods, a shaft having a cutter of less width than the width of the bearing and of less diameter 120 than the internal diameter of the bearing, a crank pin paralleling the shaft in spaced relation thereto and adapted to engage in the crank pin bearing of the connecting rod to provide a bearing about which the connecting 125 130

- rod may be oscillated to bring opposite faces of the bearing into engagement with said cutter.
4. In apparatus for forming oil pockets in the crank shaft bearings of connecting rods, a shaft having a cutter of less width than the width of the bearing and of less diameter than the internal diameter of the bearing, a crank pin paralleling the shaft in spaced relation thereto and adapted to engage in the crank pin bearing of the connecting rod to provide a bearing about which the connecting rod may be oscillated to bring opposite faces of the bearing into engagement with said cutter, said crank pin being adjustable toward and away from the shaft.
5. In apparatus for forming oil pockets in the crank shaft bearings of connecting rods, a shaft having a cutter of less width than the width of the bearing and of less diameter than the internal diameter of the bearing, a crank pin paralleling the shaft in spaced relation thereto and adapted to engage in the crank pin bearing of the connecting rod to provide a bearing about which the connecting rod may be oscillated to bring opposite faces of the bearing into engagement with said cutter, said crank pin being adjustable toward and away from the shaft.
6. In apparatus for forming oil pockets in the crank shaft bearings of connecting rods, a shaft having a cutter of less width than the width of the bearing and of less diameter than the internal diameter of the bearing, a crank pin paralleling the shaft in spaced relation thereto and adapted to engage in the crank pin bearing of the connecting rod to provide a bearing about which the connecting rod may be oscillated to bring opposite faces of the bearing into engagement with said cutter, and means intermediate the crank pin and shaft for engaging the side face of the connecting rod to maintain the same in proper alignment with the cutter.
7. In apparatus for forming oil pockets in the crank shaft bearings of connecting rods, a shaft having a cutter of less width than the width of the bearing and of less diameter than the internal diameter of the bearing, a crank pin paralleling the shaft in spaced relation thereto and adapted to engage in the crank pin bearing of the connecting rod to provide a bearing about which the connecting rod may be oscillated to bring opposite faces of the bearing into engagement with said cutter, and means intermediate the crank pin and shaft for engaging the side face of the connecting rod to maintain the same in proper alignment with the cutter, said means being adjustable longitudinally of the shaft.
8. In apparatus for forming oil pockets in the crank shaft bearings of connecting rods, a shaft having a cutter of less width than the width of the bearing and of less diameter than the internal diameter of the bearing, a crank pin paralleling the shaft in spaced relation thereto and adapted to engage in the crank pin bearing of the connecting rod to provide a bearing about which the connecting rod may be oscillated to bring opposite faces of the bearing into engagement with said cutter, said crank pin being adjustable toward and away from the shaft, and means disposed intermediate said crank pin and shaft for engaging the side face of a connecting rod to guide the same during oscillation thereof, said means being adjustable longitudinally of the shaft.
9. Apparatus for forming transversely extending grooves at the ends of the bearing faces of semi-cylindrical bearings comprising a shaft, means for rotating the shaft, a cutter carried by the shaft and having oppositely inclined side cutting faces, a platform adapted to receive the end faces of the bearing to be grooved having an opening through which the cutter may project, and means upon said platform for guiding the bearing in its passage over the cutter protecting the middle of the bearing but exposing the cutting faces of the cutter for engagement with the bearing.
10. Apparatus for forming transversely extending grooves at the ends of the bearing faces of semi-cylindrical bearings comprising a shaft, means for rotating the shaft, a cutter carried by the shaft and having oppositely inclined side cutting faces, a platform adapted to receive the end faces of the bearing to be grooved having an opening through which the cutter may project, and means upon said platform for guiding the bearing in its passage over the cutter, protecting the middle of the bearing but exposing the cutting faces of the cutter for engagement with the bearing, said platform being adjustable toward and away from said shaft.
11. Apparatus for forming transversely extending grooves at the ends of the bearing faces of semi-cylindrical bearings comprising a shaft, means for rotating the shaft, a cutter carried by the shaft and having oppositely inclined side cutting faces, a platform adapted to receive the end faces of the bearing to be grooved having an opening through which the cutter may project, and means upon said platform for guiding the bearing in its passage over the cutter exposing the cutting faces of the cutter for engagement with the bearing, comprising a semi-cylindrical bar secured to the upper surface of the platform and extending over said opening, said bar being less in width than the cutter and being notched for the reception of the periphery of the cutter and to expose the cut-

ting faces thereof, the bar having the same diameter as the bearing.

12. Apparatus for forming transversely extending grooves at the ends of the bearing faces of semi-cylindrical bearings comprising a shaft, means for rotating the shaft, a cutter carried by the shaft and having oppositely inclined side cutting faces, a platform adapted to receive the end faces of the bearing to be grooved having an opening through which the cutter may project, and means upon said platform for guiding the bearing in its passage over the cutter exposing the cutting faces of the cutter for engagement with the bearing, said platform being adjustable toward and away from said shaft, comprising a semi-cylindrical bar secured to the upper surface of the platform and extending over said opening, said bar being notched for the reception of the periphery of the cutter and to expose the cutting faces thereof, the bar having the same diameter as the bearing.

13. In apparatus for forming a diagonal oil groove in bearings which are formed in sections each of which has a pair of apertured ears for the reception of securing elements holding the sections in assembled relation, said apparatus comprising a shaft, a base therefor on which said shaft is rotatably mounted, the base adjacent one end of the shaft having an upwardly extending bracket extending beneath the shaft and having upwardly projecting pins disposed on each side of the shaft and diagonally with relation to each other and to the length of the shaft, the pins being adapted to extend through the apertured ears in a bearing section to thus hold the bearing section with its bearing axis at an inclination to the longitudinal axis of the shaft, a cutter carried by the shaft, and means for rotating the shaft.

In testimony whereof I hereunto affix my signature.

CLIFFORD T. SONDELEY.
